UNITED STATES PATENT OFFICE.

JOHN CUTHBERTSON, OF LOWELL, MASSACHUSETTS.

TENSION DEVICE FOR LOOM-SHUTTLES.

SPECIFICATION forming part of Letters Patent No. 448,475, dated March 17, 1891.

Application filed February 8, 1890. Serial No. 339,753. (No model.)

To all whom it may concern:

Be it known that I, JOHN CUTHBERTSON, of Lowell, in the county of Middlesex, State of Massachusetts, have invented certain new 5 and useful Improvements in Tension Devices for Loom-Shuttles, of which the following is a description sufficiently full, clear, and exact to enable any person skilled in the art or science to which said invention appertains to 10 make and use the same, reference being had to the accompanying drawings, forming part of this specification, in which—

Figure 1 is a plan view of a shuttle provided with my improvement; Fig. 2 is a side 15 elevation of the same with the side broken away to show the tension device, and Fig. 3 is a vertical section taken on line xx in Fig. 1.

Like letters of reference indicate corresponding parts in the different figures of the 20 drawings.

My invention relates to an adjustable tension mechanism for the filling-thread in loom-shuttles; and it consists in certain novel features hereinafter fully set forth and claimed, 25 the object being to produce a simpler, cheaper, and more effective device of this character than is now in ordinary use.

The nature and operation of the improvement will be readily understood by all 30 conversant with such matters from the following explanation.

In the drawings, A represents the body of the shuttle, and B the thread.

The shuttle is provided with an eye b opening into the bobbin-chamber in the usual manner. On the vertical wall of the bobbin-chamber at the right, as viewed in Fig. 1, a plate d is secured, and a lever f is pivoted to swing vertically on said plate, the upper end 35 of said lever being provided with a head g, which, in its normal position, is flush or nearly flush with the top of the chamber-wall, where it may be readily manipulated by the thumb of the operator when threading the shuttle. 40 A horizontally-arranged arm h is secured to the forward end of the lever f and projects laterally across the bobbin-chamber parallel with the shuttle-eye. The outer end of said arm is provided with a vertical stud or projection i, (see Fig. 3,) which engages the bottom of said chamber, in which a horizontal wear-plate j is secured. A coiled spring k

has one end secured to the plate d and passes around the pivot of the lever f, said spring acting torsionally to hold the lever-arm h depressed or in engagement with the plate j. To the upper edge of the plate d a cam-block m is secured by a set-screw p, said block being in engagement with the upper or free end of the lever f and serving as a stop to regulate the movement of said lever. A horizontally-arranged rod q extends from the plate d to the opposite wall of the bobbin-chamber parallel with the lever-arm h and disposed above said arm, as shown in Fig. 3. 65 This rod may be of a length to fit tightly between the wall and the plate, being held in position by endwise pressure or friction. It may therefore be adjusted by lateral pressure into different positions in the chamber. 70 The edge of the wear-plate j adjacent to the shuttle-eye b is turned vertically upward, forming a partition t between said eye and the lever-arm h.

In the use of my improvement, the thread 75 B is passed from the bobbin over the rod q. The head or thumb piece g of the lever f being depressed, its arm h is elevated to permit the thread to be readily passed under said arm. From thence it is carried over the 80 projection t and threaded through the eye b in the usual manner. The lever being released its arm h is forced downward by the spring k. The thread now being in engagement with the rod q, lever-arm h, and projection t before it passes through the eye, the friction of the thread upon these parts restrains its passage through the shuttle-eye, and a constant tension is thereby exerted on 85 said thread. Small knots or bunches can 90 readily pass through the tension mechanism without breaking the filling.

It is frequently the custom to steam filling-thread to prevent it from kinking as it leaves the shuttle and making imperfect cloth. This 95 process rapidly destroys the bobbins and renders the filling very tender and liable to break. My invention overcomes these objections, the friction of the thread passing over the obstructions offered by the rod, lever, and partition, as described, readily straightening the thread and causing it to pass smoothly through the eye. By moving the cam-block m outward against the lever f, so as to restrict the

fall of the lever-arm *h*, the tension may be readily lessened. By moving the rod *q* forward in the bobbin-chamber and nearer the vertical plane of the lever-arm *h*, the tension on the thread will be thereby increased, said thread passing over said rod at a more acute angle in a manner readily understood without a more explicit description.

The projection *i* on the lever-arm *h* prevents the thread from accidentally passing from under said arm. When said arm is elevated by depressing the lever-head *g*, as described, the shuttle may be threaded as readily as when no tension mechanism is employed.

Having thus explained my invention, what I claim is—

1. The combination of a shuttle - body, a spring-actuated tension-lever pivoted within 20 the bobbin - chamber thereof, an adjustable stop for said lever, an arm on said lever projecting into the bobbin-chamber, and a rod extending across said chamber parallel with said arm, substantially as described.

2. The combination of a shuttle - body, a spring-actuated tension-lever *f*, pivoted within the bobbin - chamber thereof and provided with the arm *h*, having the projection *i*, and the rod *q*, extending across said chamber, substantially as described.

3. The combination of a shuttle-body provided with a bobbin-chamber, a thread eye

and a flange or partition in the bobbin-chamber adjacent to said eye, a rod extending across said chamber, and a spring-actuated 35 tension - lever pivoted within said chamber and provided with a horizontal arm engaging the bottom thereof between said rod and flange, substantially as described.

4. The combination of a shuttle - body, a 40 spring-actuated tension-lever pivoted within the bobbin-chamber thereof, an adjustable stop for said lever, and a horizontal arm on said lever projecting into the bobbin-chamber and provided with a vertical projection 45 engaging the bottom thereof, substantially as described.

5. The combination of a shuttle - body, a spring-actuated tension-lever pivoted within 50 the bobbin-chamber and having an arm projecting therein adjacent to the thread-eye end, and a cam-block, as *m*, pivoted to the wall of said chamber in engagement with said lever and serving as an adjustable stop therefor.

6. The combination of the body *A*, the lever *f*, pivoted to the wall of the bobbin-chamber thereof and having the arm *h*, provided with the stud *i*, the rod *q*, the adjustable stop *m*, and the partition *t*, substantially as described. 60
